WAFFLE IRON

Filed April 7, 1939

Inventor

Elmer B. Borg.

UNITED STATES PATENT OFFICE

118,811

DESIGN FOR A WAFFLE IRON

Elmer B. Borg, Los Angeles, Calif.

Application April 7, 1939, Serial No. 84,127

Term of patent 3½ years

To all whom it may concern:

Be it known that I, Elmer B. Borg, a citizen of the United States, residing at Los Angeles, in the county of Los Angeles and the State of California, have invented a new, original, and ornamental Design for a Waffle Iron, of which the following is a specification, reference being had to the accompanying drawing, forming part thereof. The figure is a perspective view of a waffle iron, showing my design.

I claim:

The ornamental design for a waffle iron, as shown.

ELMER B. BORG.
